US0D1099037S

(12) **United States Design Patent** (10) **Patent No.:** **US D1,099,037 S**
(45) **Date of Patent:** **** Oct. 21, 2025**

(54) **POWER DISTRIBUTION UNIT**

(71) Applicant: **Caterpillar Inc.**, Peoria, IL (US)

(72) Inventors: **Yingying Kuai**, Dunlap, IL (US); **Meng Xue**, Wuxi (CN); **Kai Zhu**, Wuxi (CN); **Wei Cheng**, Wuxi (CN); **Baobao Liang**, Wuxi (CN)

(73) Assignee: **Caterpillar Inc.**, Peoria, IL (US)

(**) Term: **15 Years**

(21) Appl. No.: **29/916,016**

(22) Filed: **Nov. 7, 2023**

(51) **LOC (15) Cl.** **13-02**

(52) **U.S. Cl.**

USPC **D13/123**

CLAIM

The ornamental design for a power distribution unit as shown and described.

DESCRIPTION

FIG. 1 is a perspective view of a power distribution unit showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines depict portions of the power distribution unit which form no part of the claimed design.

1 Claim, 6 Drawing Sheets
